[57] CLAIM

The ornamental design for a tape mounted electric connector package, as shown and described.

DESCRIPTION

FIG. 1 is a front elevational view of a tape mounted electric connector package showing my new design;

FIG. 2 is a rear elevational view thereof;

FIG. 3 is a sectional view thereof, taken along line 3—3 in FIG. 1;

FIG. 4 is a sectional view thereof, taken along line 4—4 in FIG. 1;

FIG. 5 is a right side elevational view thereof, the left side elevational view being mirror image;

FIG. 6 is a top plan view thereof; and,

FIG. 7 is a bottom plan view thereof.

The claimed ornamental design is continuous throughout the entire length thereof and a part of the entire length is shown, in all views, to indicate intermediate length thereof, and the undisclosed end is identical in appearance to the end shown.
